[57] CLAIM

The ornamental design for a mounting bracket, substantially as shown and described.

DESCRIPTION

FIG. 1 is a perspective view of a mounting bracket showing our new design;

FIG. 2 is a front elevational view of the mounting bracket of FIG. 1;

FIG. 3 is a side elevational view taken from the left of FIG. 2 which is a mirror image of side elevational view taken from the right of FIG. 1; and

FIG. 4 is a bottom view of the mounting bracket shown in FIG. 2.
